Primary Examiner — Patricia A Palasik(74) *Attorney, Agent, or Firm* — Kyle Liudahl(57) **CLAIM**

The ornamental design for a lubrication dispense valve, as shown and described.

DESCRIPTION

FIG. 1 is a perspective view of a lubrication dispense valve;
 FIG. 2 is a front view thereof,
 FIG. 3 is a rear side view thereof,
 FIG. 4 is a top view thereof,
 FIG. 5 is a bottom side view thereof;
 FIG. 6 is a left view thereof; and,
 FIG. 7 is a right view of a lubrication dispense valve.
